CLAIM

The ornamental design for an automatic feeding device for pets, as shown and described.

DESCRIPTION

FIG. 1 is a front elevational view of an automatic feeding device for pets showing my new design; FIG. 2 is a rear elevational view thereof; FIG. 3 is a left side view thereof; FIG. 4 is a right side view thereof; FIG. 5 is a top plan view thereof; FIG. 6 is a bottom plan view thereof; FIG. 7 is a top, front and left side perspective view thereof; FIG. 8 is a top, front and right side perspective view thereof; and, FIG. 9 is a bottom, rear and right side perspective view thereof.

The broken lines in the drawings illustrate portions of the automatic feeding device for pets which form no part of the claimed design.
